UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

OUTLET-FITTING.

1,395,084.

Specification of Letters Patent. Patented Oct. 25, 1921.

Application filed June 28, 1915. Serial No. 36,819.

To all whom it may concern:

Be it known that I, REUBEN B. BENJAMIN, a citizen of the United States, residing at Chicago, in the county of Cook and State 5 of Illinois, have invented new and useful Improvements in Outlet-Fittings, of which the following is a full, clear, concise, and exact description, reference being had to the accompanying drawing, forming a part of 10 this specification.

My invention relates to outlet fittings.

One of the objects of my invention is to provide a fitting which will have improved means for making electrical connection with 15 the outlet and supporting a lamp device such as a shade or other fixture.

In the drawings, in which I have shown several embodiments of my invention—

Figure 1 is an axial section of an outlet 20 box in which the cover is supported by a strap secured to the conduit, and in which a special connector for supporting a fixture having a stem support and making electrical connection with the conduit is provided;

Fig. 2 is a section on the line 2—2 of Fig. 25 1 showing center and side contacts of the connector and the manner in which they are secured on the base;

Fig. 3 is a section substantially on the line 30 3—3 of Fig. 2 showing the arrangement of the binding plates;

Fig. 4 is an axial section of the modification 35 in which the outlet box cover is secured to the ears of the outlet box and is provided with a threaded connector for supporting a lamp shade or other device, an ornamental cover also being provided; and

Fig. 5 is an axial section showing my 40 invention in connection with a connector for supporting a fixture having a chain support.

Referring now to the drawings in detail, and first to Figs. 1, 2 and 3, I have here shown my invention in connection with an outlet box 10 having an opening 11 therein 45 through which extends a conduit 12 forming an outlet for the feed circuit. The outlet box is secured in place by means of a nut 13 threaded on the end of the conduit. A strap 14 for supporting the outlet 50 box cover has an opening through which the end of the conduit extends and is held in place on the conduit by means of a nut 15. The cover 16 is held in place on the conduit by means of screws 17 threaded in the 55 ends of the strap 14. Secured to the cover

16 is a supporting member 18 which may be of sheet metal threaded at 19 to engage a suitable connector and reduced, as shown at 20, to form a shoulder for engagement with the shoulder of a receptacle, and 60 flanged over as shown at 21 to secure it in place on the cover 16. A reinforcing washer 22 may be provided to strengthen the connection between the member 18 and the cover 16. The member 18 is provided with 65 a plurality of stamped up tongues 23 which extend inwardly to hold the receptacle 24 in place. The receptacle or connector device 24 is provided with the usual center and shell contacts 25 and 26 supported on 70 an insulating base 26^a, which base is provided with a flange or shoulder 27 in engagement with the shoulder 20 of the member 18 and is recessed at 28 to receive the spring tongues 23 which hold the receptacle 75 in position. The receptacle is provided with suitable binding terminals 28^a. Supported by the member 18 is a combination connector and supporting device 29 having a 80 U-shaped spring center contact 30 for engagement with the center contact of the receptacle, an insulating base portion 31 for supporting the center contact, side contacts 32 for engagement with the shell contact 26 of the receptacle, binding terminals 33 and 85 34 for the lamp connection, an insulating base portion 35 for supporting the side contacts and binding terminals, and a mechanical connecting device 36 for connecting a lamp fixture having a stem support with the 90 supporting member 18. The mechanical connecting device 36 comprises a threaded shell portion 37 for engaging the threaded portion 19 of the member 18, a bushing 38 for engagement with the threaded end 38^a 95 of a stem for supporting a lamp fixture such as an electrolier, and a cup member 39 in which the insulating base 35 is seated and to which the threaded shell is connected. The base portion 31 is recessed at its upper 100 end as shown at 40 to receive the center contact 30 which is held in place on the base portion by means of a hollow rivet or eyelet 41. The center contact 30 is electrically connected to the binding plate 42 by means of a screw 43 which also serves to hold the two base portions 31 and 35 together. The binding plate 42 is held in place on the base portion 35 by means of a screw 44 and is provided with a binding screw 45 for con- 110

nection with one of the conductors leading to the lamp.

Each side contact 32 comprises a spring tongue portion 46 seated in a recess 47 in the base 31, and a base portion 48 seated in a recess 49 in the portion 35. These side contacts 32 are both electrically connected to a yoke shaped binding plate 50 by means of screws 51 having their heads seated in recesses 52 in the base 35, these screws extending through openings 52^a in the base portions 48 of the side contacts and being threaded into the binding plate 50. A binding screw 53 is provided for connection with 10 the other conductor leading to the lamp.

The cup member 39 is provided with an outwardly extending flange 54 over which the lower end of the threaded member 37 is flanged, as shown at 55. The bushing 38 is 20 provided with a hexagonal flange 56 which is located in a hexagonal recess 57 in the base portion 35. The cup member 39 may be flanged over as shown at 58 beneath the flange 56 to strengthen the connection between the bushing and cup member. For holding the base portion 35 in position in the cup member 39 a retaining member 59 is provided which may be a split sheet metal ring having an inwardly extending flange 25 portion 60 for engagement with the upper face of the base 35. The threaded member 37 is flanged over as shown at 61 to hold the retaining member 59 after it has been slipped into place.

35 The use and operation of the device of this modification is as follows: The receptacle 24 is slipped in place within the supporting member 18, the spring tongues 23 yielding to permit this and snapping into 40 place in the recesses 28 when the receptacle is properly positioned. The feed wires are then connected to the binding terminals 28^a of the receptacle 24 after which the cover 16 carrying the receptacle is secured in place 45 on the outlet box by means of the screws 17. Any lamp fixture having a threaded stem supported such as 38^a is connected with the bushing 38 by threading the stem 38^a therein. The terminals 33 and 34 are then 50 wired and the base portions 31 and 35 secured together by means of the screw 43. The retaining ring 59 is then slipped into place to hold the base 35 in position in the cup 39. A member, capable of rotary movement and including the parts 54, 55 and 37, is threaded as shown at 37 to provide fastening means operable upon a rotary movement of said member to co-act with threaded portion 19 to mechanically connect the 55 fixture to the outlet box cover. As the shell portion 37 is screwed into the threaded portion 19 the side contacts 32 and center contact 30 will be brought into contact with the center and shell contacts 25 and 26 of 60 65 the receptacle 24 to complete the electrical

connection between the outlet and the fixture. The circuit will be from the center contact 25 to the contact 30, screw 43, binding plate 42, binding screw 45, lamp circuit, binding screw 53, binding plate 50 and side contacts 32 to the threaded shell contact 26 of the receptacle.

In the modification of Fig. 4 I have shown my invention in connection with an outlet box 62 having a cover 63 which may be of sheet steel which is connected to the outlet box by means of screws 64 extending through openings in the cover and threaded into the ears 65 of the outlet box. The cover 63 has an opening 66 through which extends the reduced portion 67 of a supporting device 68 which has a portion flanged over above the cover of the outlet box to hold the supporting device 68 in place. The supporting device has a threaded portion 70 for supporting any suitable lamp device, such as a lamp shade, and is provided with stamped up tongues 71 for holding a receptacle in place. The receptacle used with this device may be similar in all respects to the receptacle 24 of the modification of Fig. 1. An ornamental cover 72 is provided having an opening 73 therein to receive the threaded portion 70 of the supporting device 68. This cover 72 is slit adjacent the opening 73, one edge of the slit being bent up and the other being bent down as shown at 74 to cause the edge of the opening 73 to assume a helical shape to conform to the threads on the threaded portion 70. A shade 75 having a threaded neck portion 76 is secured to the supporting member 68, the upper edge of which neck portion 76 may be flanged inwardly as shown at 77 for engagement with the flange 27 on the receptacle 24. The use of the device of this modification is as follows:

The receptacle 24 is slipped in place within the supporting device 68 and the feed wires from the outlet are connected thereto. The cover 63 is then secured to the outlet box by means of the screws 64; the ornamental cover 72 is then screwed into place after which the shade 75 is attached.

In Fig. 5 I have shown my invention in connection with a supporting device 78 for a chain supported lamp fixture. This supporting device comprises a threaded ring 79 to which a plurality of hooks 80 are secured at various points for connection with the chains 81 which support any suitable lamp fixture device 82. In this modification the cover 16, supporting device 18 and receptacle 24 may be substantially the same as in the modification of Fig. 1.

The threaded portions of the supporting devices 18 and 68 provide a connection whereby any one of a comprehensive line of reflectors, shade holders, and other electrical devices may be interchangeably used.

In the claims, where the expression "lamp fixture device" is used, it will be understood to include, but not in limitation, reflectors, shade-holders, shades, electroliers, etc.

5 Having thus described my invention what I claim as new and desire to secure by Letters Patent is:—

1. In a device of the class described, a connector device adjacent to an electrical outlet, comprising an insulating base, and a wiring terminal supported thereby, and a contact also supported thereby for engagement with the contact of a coöperating connector device, said contact being electrically connected to said wiring terminal, a cover for said outlet provided with an annular connecting member, and a supporting device having an annular portion for making connection with said member, and a portion for holding said base in position with respect to said outlet, said supporting device being also provided with means for mechanically supporting a lamp fixture device.
2. A connector device provided with means for mounting it adjacent an electrical outlet comprising an insulating base, a wiring terminal supported thereby, a contact also supported thereby for engagement with the contact of a coöperating connector device, said contact being electrically connected with said wiring terminal, a cover for said outlet having an annular connecting portion, and a supporting device having an annular portion for making connection with said first portion, and a portion for holding said base in position with respect to said outlet, a cup-shaped member supported by said second annular portion, and a lamp fixture supported by said cup-shaped member.

3. An outlet fitting comprising an outlet cover, an electrical connector device located adjacent said cover, including an insulating base and a contact supported by said base for engagement with the contact of a coöperating electrical connector device, a mechanical connector member located adjacent said cover and having an internally-threaded entrance portion, and a retaining ring screwed into said threaded entrance portion, said electrical connector device having a shoulder portion on which the inner edge of said threaded ring bears inside said threaded entrance portion to hold said electrical connector member in position with respect to said outlet cover, said retaining ring being provided with means for supporting a lamp-fixture device.

4. The combination with an electric lamp fixture and a receptacle having a contact, of a plug having a contact for engaging the receptacle contact, and having a wiring terminal for the fixture wire, and common supporting means for supporting the plug and fixture in position with respect to the re-

ceptacle, comprising a ring swiveled with respect to said plug and fixture, said receptacle having a contact member extending into said swivel ring.

5. The combination with an electric lamp fixture and a receptacle having a contact, of a plug having a contact for engaging the receptacle contact, and having a wiring terminal for the fixture wire, and common supporting means for supporting the plug and fixture in position with respect to the receptacle, comprising a ring swiveled with respect to said plug and fixture, said receptacle having an insulating housing for the receptacle contact extending into said ring.

6. The combination with an outlet box cover having an opening therein, a receptacle having its outer face substantially flush with said opening, and an electric lighting fixture, of a plug having contacts for engaging the receptacle contacts, and having wiring terminals for the wires of the lighting fixture, and common supporting means for supporting said plug and fixture in position with respect to said receptacle, comprising a swivel ring swiveled with respect to said plug and fixture, and extending into and engaging the opening in the cover.

7. The combination with a receptacle having a contact, and a fixture, of a plug having a contact for engaging the receptacle contact, and having a wiring terminal for the wire for the fixture, and common supporting means for supporting the plug and fixture in position with respect to the receptacle, comprising a fixed annular connector member surrounding said receptacle and spaced therefrom, and a swivel ring swiveled with respect to said plug and fixture, and extending into the annular space between said fixed annular member and said receptacle, and detachably connected with said fixed annular member.

8. The combination with an electric lamp fixture and a receptacle having a contact, of a plug having a contact for engaging the receptacle contact, and having a wiring terminal for the fixture wire, and common supporting means for supporting the plug and fixture in position with respect to the receptacle, comprising a ring swiveled with respect to said plug, said receptacle having an insulating housing for the receptacle contact extending into said ring.

9. The combination with a receptacle having a contact, and a fixture, of a plug having a contact for engaging the receptacle contact, and having a wiring terminal for the fixture, and common supporting means for supporting the plug and fixture in position with respect to the receptacle, comprising a fixed annular connector member surrounding said receptacle and spaced

therefrom, and a ring swiveled with respect to said plug and extending into the annular space between said fixed annular member and said receptacle, and detachably connected with said fixed annular member.

10. The combination with an electric lamp fixture and a receptacle having a contact, of a plug having a contact for engaging the receptacle contact, and having a wiring terminal for the fixture wire, and supporting means for supporting the plug and fix-

ture in position with respect to the receptacle, comprising a member including connecting means operable upon a rotary movement of said member, said receptacle having 15 an insulating housing for the receptacle contact surrounded by said connecting means when the parts are connected.

In witness whereof, I have hereunto subscribed my name.

REUBEN B. BENJAMIN.
